CLYDE T. ELDREDGE, OF SAN FRANCISCO, CALIFORNIA.

HIGHWAY TRACK.

1,413,839.

Specification of Letters Patent. Patented Apr. 25, 1922.

Application filed August 18, 1921. Serial No. 493,343.

To all whom it may concern:

Be it known that I, CLYDE TALBOT ELDREDGE, a citizen of the United States, and resident of San Francisco, county of San Francisco, and State of California, have invented a new and useful Highway Track, of which the following is a specification.

The present invention relates to improvements in highway tracks and its object is to provide metal tracks for macadamized or concrete road-beds by means of strong, cheap and light rails inserted in the road-bed. Various forms may be designed for this purpose and I show in the accompanying drawings 10 three different applications of the principles involved in my invention, the three different designs, while revolving on the same principle, being selected to illustrate how the principle can be successfully applied to roads subject to heavy, medium or 15 light traffic.

In the drawing Figure 1 is a perspective view of a single track rail, designed for heavy traffic, Figure 2 a cross-sectional view of a 20 roadbed having rails designed for medium traffic embedded therein, and Figure 3 an end view of a single track rail designed for light traffic.

Referring to the drawing in detail it will be 25 noted that in the form shown in Figure 1 the top plate 1 of the rail, which is rather light in weight, is supported by the two T bars 2 placed in such a manner that the outer end 3 of the T is flush with the outer edge 4 of the 30 top plate, and the webs 6 of the T, which extend vertically into the concrete, preferably to the depth indicated in Figure 2, support two rail portions lying intermediate between the edge and the center of the top 35 plate. The web is provided, at its lower end, with a flanged base 7, which, when embedded in and covered by the concrete, serves as an anchor and firmly engages the T bar with the concrete and prevents any vertical play. 40 The top plate is secured to the T bars by means of the rivets 8 and short angle irons 9, bolted to the T bar and the top plate, as shown at 11, and secured to the web of the T bar by the bolt 14, are used to join two 45 adjoining lengths of rail.

I wish to point out that the lightness of the construction, especially as regards the edge portions of the rails, is a particular feature of my rail and that the supporting T's 50 give sufficient strength to the structure to

allow the top plate to be of comparatively light weight.

To further reinforce the structure and make a closer union between the rails and the concrete I provide a plurality of cross bars 60 16 which penetrate the web and extend transversely through the roadbed and longitudinal bars 20 secured to the cross bars, thereby binding rail and roadbed into one 65 solid structure.

The structure shown in Figure 2 differs from that of Figure 1 only in so far as it is somewhat lighter and designed for roads where the traffic is not so very heavy. The difference consists in the substitution of the 70 L bars 17 for the T bars, the horizontal portion 18 of the L bar being secured to the outer part of the top plate, and the vertical portion 19 taking the place of the web, an anchoring base 21 being provided like that in the structure shown in Figure 1.

In Figure 3 I show a construction suitable for roads of light traffic. While the general idea embodied in the other structures, that is, the supporting of a rather light plate by 80 means of webs anchored in the concrete, is preserved, this modification shows the whole rail as consisting of one inverted channel iron, the web 22 of the channel taking the place of the plate above referred to, and the 85 flanges 23 of the channels taking the place of the supporting webs of Figure 1, the anchoring base 24 serving the same purpose as in the other structures.

I claim:

1. In a highway track for a roadbed, a rail comprising a horizontal plate disposed longitudinally of the roadbed and supporting members placed on edge underneath the edge portions of the plate and embedded in the 90 roadbed, the supporting members having a flanged base for anchoring the same in the roadbed, and transverse metal members extending through the supporting members and the roadbed for combining the same into 95 a solid structure.

2. In a highway track for a roadbed, two rails running parallel to each other, each comprising a horizontal plate disposed longitudinally of the roadbed, supporting members placed on edge underneath the edge portions of the plate and embedded in the roadbed, transverse metal members extending through the supporting members and the 105 roadbed and longitudinal members crossing 110

the transverse members for binding the rails and the roadbed into one solid structure.

3. In a highway track for a roadbed, a rail comprising a horizontal plate disposed longitudinally of the roadbed, two T shaped members placed underneath the edge portions of the plate so that the outer edges are substantially flush, the webs of the T shaped members being embedded in the roadbed.

10 4. In a highway track for a roadbed, a rail

comprising a horizontal plate disposed longitudinally of the roadbed, two T shaped members placed underneath the edge portions of the plate so that the outer edges are substantially flush, the webs of the T shaped members being embedded in the roadbed, and having lateral flanges at their lower edges for anchoring the same in the roadbed.

CLYDE T. ELDREDGE.
